UNITED STATES PATENT OFFICE

EARL STANDISH BOYNTON, OF EAST ORANGE, NEW JERSEY, ASSIGNOR TO PHOTOMATON, INC., OF NEW YORK, N. Y., A CORPORATION OF NEW YORK

COOLING MEANS FOR PHOTOGRAPHIC FILM TANKS

Application filed April 14, 1930. Serial No. 444,066.

The object of the present invention is to provide means for maintaining the chemicals of a plurality of tanks in an automatic developing device at a desired temperature below that of the surrounding area, the invention being particularly applicable to the developing apparatus for photographic film strips, forming the subject of A. M. Josepho Patent No. 1,656,522 of January 17, 1928.

10 The principle of the cooling means is the application of a single cooling medium simultaneously to a plurality of developing tanks through the intermediary of heat-transmission plates, or a single plate, whereby it is unnecessary to obstruct the individual developing tanks, as by placing therein cooling tubes for the flow of a refrigerating medium as heretofore proposed.

The invention will be understood by reference to the accompanying drawings, in which—

Fig. 1 is a view in elevation of a developing apparatus casing supporting a plurality of individual tanks or chambers, and showing applied thereto cooling means constructed in accordance with the invention, said means being partly broken away,

Fig. 2 is a plan view of the same;

Fig. 3 is a transverse section on the line 3—3, Fig. 1, looking in the direction of the arrows, and

Fig. 4 is an enlarged view of the lower corner of the cooling means shown in Fig. 3 to illustrate the liquid-tight connections of the cooling means with the photographic film tank-casing.

In a certain type of developing apparatus for photographic film strips, such as that disclosed in the aforesaid Patent No. 1,656,522, a plurality of vertically disposed tanks are employed for containing various chemical solutions and washing medium for the strips as they pass from one end of the developing apparatus to the other.

In Figure 1 the vertically extending division walls of the tanks are indicated by the dotted lines 1, said walls being indicated in full lines by the same numeral in Figure 2. Inasmuch as a plurality of the tanks contain chemicals, their casing and division walls

must be constructed of acid resisting material such as hard rubber, and owing to the necessity for condensing the structure to small compass, particularly as to the length of the tank, there being sometimes as many as nine tanks or chambers, each containing conveying mechanism for the strip, it has been disadvantageous to place cooling means, such as conveyor tubes for a refrigerant, within the tanks. The present invention avoids the necessity for such cooling tubes by the application to the tank casing 2 of a cooling box 3, having heat transmission means in communication with those tanks which require cooling. In the present instance cooling box 3 is formed as a member separate from the tank casing wall 2, and therefore it is formed with a lower flange 4 and side flanges 5. Intermediate the flanges and the casing wall 2 there is placed a suitable packing, and the flanges are then bolted to the casing wall by means of the bolts 6.

Any other suitable means for securing the cooling box in position may be employed, and if desired the box may be formed integrally with wall 2. In the present instance the tanks indicated at a, b, c, d and e are those which hold, of the series, chemical solutions for treatment of the strip, intermediate tanks such as f, g, h, i being washing tanks. The casing wall 2 opposite tank d has been cut away in rectangular form, within cooling box 3, to form an aperture 7, Figure 3. This aperture intermediate the tank d and the cooling box is closed by a plate 8 of stainless steel or other material capable of heat conduction but impervious to the chemical used in the tank. Plate 8 is larger than aperture 7 so that it has a portion which lies upon the casing wall surrounding the aperture, the plate being held in place by a plurality of bolts 9, suitable packing being placed intermediate the plate and the casing wall 2. A similar plate 10 is applied to an aperture 11 in the casing wall 2 opposite tank c and a plate 12 is similarly disposed with respect to an aperture opposite tank e. A fourth plate 13 covers apertures formed in the casing wall 2 opposite both tanks a and b. In the present instance the section of the cool-

ing box opposite tank *e* is of relatively small area. The cooling box may contain the heat absorption coils of a refrigerating machine and may receive brine or any other cooling medium.

5 In the operation of the device, heat within tanks *a*, *b*, *c*, *d* and *e* will be exchanged by the plates 8, 10, 12 and 13 to the brine or other cooling medium and the desired temperature within each tank may be maintained by proportioning the cooling box 3 and the heat exchange plates to the area of the tanks.

10 By the above means cooling of the photographic chemical solutions is obtained without the necessity of obstructing the tanks by cooling pipes and the like for the flow of a refrigerating medium. When the cooling box is a unit independent of the tank casing, it may be provided with supporting means 15 other than or in addition to the bolts 6, as for example the vertical support 14 shown in Figure 3.

20 Having described my invention what I claim and desire to secure by Letters Patent is as follows:

25 In combination with a plurality of photographic-film treating tanks arranged side by side, cooling means comprising a cooling box adapted to receive a liquid cooling medium, apertures formed in the walls of a plurality of said tanks, said apertures being in register with the cooling box, and a plurality of heat-exchange plates connected to the marginal walls of the apertures and separating 30 the said tanks from the cooling box.

35 In testimony whereof I have signed my name to this specification.

EARL STANDISH BOYNTON.
